UNITED STATES PATENT OFFICE

RAY W. ARMS, OF CHICAGO, ILLINOIS, ASSIGNOR TO ROBERTS AND SCHAEFER COMPANY, OF CHICAGO, ILLINOIS, A CORPORATION OF ILLINOIS

PROCESS OF CLEANING COAL

Original application filed May 23, 1927, Serial No. 193,468. Divided and this application filed March 10, 1928. Serial No. 260,565.

My invention relates to dust collecting systems for air separating tables and the like and to a process of handling dust laden air therefrom. It has for one object to provide a new and improved apparatus and process whereby dust generated air set free by an air separating table may be separated from the air returned to the system and whereby the volume of air which has to be separately treated for dust separation will be reduced. Other objects will appear from time to time throughout the specification and claims. This application is a division of my co-pending application Serial Number 193,468 filed May 23, 1927.

My invention is illustrated more or less diagrammatically in the accompanying drawings, wherein—

Figure 1 is a side elevation of an apparatus embodying my invention;

Figure 2 is an end elevation.

Like parts are indicated by like characters throughout the specification and drawings.

A is an air pervious material separating deck. It is reciprocated by a pulley A¹ driving a crank A² and a link A³. A⁴ is a feed shelf reciprocating with the deck adapted to receive coal or other material to be treated which is discharged thereupon through a spout A⁵ from a hopper A⁶. A⁷ A⁸ A⁹ are material discharge chutes which collect and discharge the separated material from the table or deck.

B is a blower driven by a motor B¹ and discharging air under pressure through the chimney B² to the underside of the pervious deck. B³ is a dust hood located above the deck. B⁴ is a bellows of flexible or other suitable fabric extending down from the lower edge of the hood to the deck. This bellows extending down to the deck throughout the major portion of its periphery only so much of the space between the hood and the deck being open as is necessary to permit the attendant to inspect the operation of the machine. B¹⁴ is a funnel forming part of the hood B³ discharging into a pipe B⁵ which pipe leads to any suitable dust collecting and separating apparatus. This funnel is located over the feed corner of the table or deck, that

is,—that part of the deck or table where the major portion of the dust originates. The dust separator since its details form no part of the invention is only shown diagrammatically as at B⁶.

Extending from the dust hood B³ in an air recirculation pipe C. It discharges into a dust trap C¹ and a pipe C² leads therefrom to the intake side of the fan B. C³ is a conveyor adapted to carry off the dust brought down from the air by the dust trap or settling chamber C¹. C⁴ is an adjusting make up air supply leading to the intake of the fan. The necessity of this is caused by the fact that part of the air taken from the hood B³ is carried off to the dust separator and part of it comes back to the fan or blower. Some of the make up air comes in between the hood B³ and the deck and the adjustable make up opening will be so set and controlled either manually or automatically that there will always be an inflow of air between the hood and the deck and never an outflow.

The result of this is that no dust laden air gets out into the room or house in which the table is operating. The tendency of air flow is always inward in the entire system except that part of it leading from the blower to the underside of the deck which alone is not under sub-atmospheric pressure. Thus there is no tendency for dust to escape anywhere from the system into the room.

Except in connection with the very finest screens the presence of dust in the recirculated air and therefore in the air blown up through the screen or pervious deck to float and assist in separating the material, is not a detriment but an advantage because it is understood that in connection with dust separating the flowing stream of finely divided material travels along a separating table under the influence of gravity, the reciprocation of the table and the floating effect of the air. Experience shows that if anything can be done to increase the specific gravity of the air or gas stream the material can be floated with a decreased velocity, pressure and volume of air. The presence of dust then in the air fed to the underside of the pervious deck and traveling up through it and through the

bed of material increasing to some extent as it does the specific gravity of the air, helps rather than hinders in the separating operation.

5 Experience shows that there is a saturation point at which the air stream will carry no further dust. Beyond that point dust may be deposited out in the dust trap or may be screened out by the bed of traveling material to be treated.

10 Only that relatively small proportion of the air having the maximum amount of dust is drawn out through the funnel and discharged to a separate dust collector. Thus a 15 relatively small dust collector can be used and a high degree of efficiency in dust collection can be obtained. It is ordinarily not desirable to attempt to recirculate all the air because unless the space between the hood 20 and the deck is made air tight there will be a leakage inward about the edges of the deck and this constant increase in the amount of air drawn away from the deck over that fed to it must be compensated for by bleeding off 25 some of the air and recirculating the balance. Moreover a never ending recirculation might result in so saturating the recirculated air with dust and dirt particles that the screening system might become clogged.

30 While I have shown part of the air taken from the hood and discharged through a dust separator, it is obvious that such air may be discharged into any suitable system and the dust separator needs not to be of any particular type and might take any number of different forms and in fact it is conceivable that many things might be done to the air before it reaches the dust separator or it might merely be discharged away from the system.

40 One of the important reasons for taking some of the air from the hood and discharging it either to a separator or hood is that by doing this it becomes possible to keep all the air except that portion below the deck under 45 sub-atmospheric pressure so that all leaks will be in, instead of out, and there will be no tendency for dust laden air to escape from the system into the room or house where the system is located.

50 While I have shown my device as applied to the cleaning of coal and have so described and claim it, it is obvious that coal is merely one of the materials which might be cleaned, it happening to be that coal is the material 55 which applicant is now cleaning. Quite obviously, however, other materials which would generate dust could be cleaned by the same method and I wish it understood that where I refer to a coal cleaning system, I am 60 using the term "coal" merely for the purpose of illustration.

I claim:

1. The process of cleaning coal by air which consists in forcing a high pressure 65 stream of air through a flowing bed of coal,

said stream including a portion of the dust laden air from above the bed together with an additional supply of air, withdrawing the resultant air from above the bed, recirculating part of it through the coal bed and withdrawing the remainder from the system.

2. The process of cleaning coal by air which consists in forcing a high pressure stream of air through a flowing bed of coal, said stream including a portion of the dust laden air from above the bed together with an additional supply of air, withdrawing the resultant air from above the bed, recirculating part of it through the coal bed and withdrawing the remainder from the system, the quantity of air withdrawn from the system being substantially equal to the additional quantity of air added to the system above the bed.

3. The process of treating dust-laden air from air cleaning systems wherein cleaning takes place in a stratifying zone in accordance with specific gravity, which consists in withdrawing a part of the spent dust-laden air, from the system above the zone and in re-circulating the balance of the dust-laden air through the zone.

4. The process of treating dust-laden air from air cleaning systems wherein cleaning takes place in a stratifying zone in accordance with specific gravity, which consists in withdrawing a part of the spent dust-laden air, from the system above the zone, and in re-circulating the balance of the dust-laden air through the zone while maintaining all parts of the system except that part which conducts the working air under pressure to the stratifying zone, under sub-atmospheric pressure.

Signed at Chicago, county of Cook and State of Illinois, this 6th day of March, 1928.
